UNITED STATES PATENT OFFICE.

JAMES SMITH, OF TAMPA, FLORIDA, ASSIGNOR TO THE PALM CRAFT COMPANY, OF TAMPA, FLORIDA, A CORPORATION OF FLORIDA.

DESIGN FOR A LAMP.

57,939.

Specification for Design.

Patented May 17, 1921.

Application filed November 6, 1920. Serial No. 422,396. Term of patent 14 years.

To all whom it may concern:

Be it known that I, JAMES SMITH, a citizen of the United States, residing at Tampa, in the county of Hillsborough and State of Florida, have invented a new, original, and ornamental Design for a Lamp, of which the following is a specification, reference being had to the accompanying drawings, forming a part thereof.

The figure is a perspective view of the lamp showing my new design.

I claim:

The ornamental design for a lamp as shown.

JAMES SMITH.
